United States Patent Office.

ALBERT A. CHITTENDEN, OF BOSTON, MASSACHUSETTS.

Letters Patent No. 70,958, dated November 19, 1867.

IMPROVED IRONING-TABLE.

The Schedule referred to in these Letters Patent and making part of the same.

TO ALL WHOM IT MAY CONCERN:

Be it known that I, ALBERT A. CHITTENDEN, of Boston, in the county of Suffolk, and State of Massachusetts, have invented a new and improved Ironing-Table; and I do hereby declare that the following is a full, clear, and exact description thereof, which will enable others skilled in the art to make and use the same, reference being had to the accompanying drawings, forming part of this specification.

This invention relates to an improved ironing-table, and consists of a table or skirt-board, supported at one end upon a rail secured to the wall and setting under a bracket. The table may be further supported by a leg, as shown in the accompanying drawings, in which—

Figure 1 is a top view.

Figure 2 a section at the line xx of my improved ironing-table.

Similar letters of reference indicate like parts.

A is the table or skirt-board, held by the bent iron rod B, the ends whereof, $b b$, pivot in the frame C, mortised at c , to receive the end of the table, as shown in fig. 2. A couple of slats, $a a$, on the under side of the table A, form a groove to receive the rod B. D is a stand for the iron, hinged at d , and folding into the recess E, when not in use. A button, f , closes over the rod B, when introduced into the groove formed by the two slats $a a$. When the table is long, or extra strength is required, a leg, G, may be hinged at g , and rest either upon the floor or against the wall and flooring, as shown in fig. 2. The table can be turned up against the wall and hung by the rod B, or altogether removed, when not in use. The button f will also serve to keep up leg G, when applied to table, but not required to be used. The table may also be supported on one or more brackets in place of the rod B, and be furnished with a circular lip curving upwards, grooving into a shelf also furnished with a circular lip curving downwards.

I claim as new, and desire to secure by Letters Patent—

The movable table A, in combination with the rod B and frame C, or their respective equivalents, substantially as and for the purpose described.

ALBERT A. CHITTENDEN.
